UNITED STATES PATENT OFFICE.

JOHN J. TOBIN AND FRANK J. GALLAGHER, OF SAYRE, PENNSYLVANIA.

SPIRAL PROPELLER FOR SHIPS.

1,196,176.

Specification of Letters Patent. Patented Aug. 29, 1916.

Application filed October 28, 1915. Serial No. 58,418.

To all whom it may concern:

Be it known that we, JOHN J. TOBIN and FRANK J. GALLAGHER, citizens of the United States, residing at Sayre, in the county of Bradford and State of Pennsylvania, have invented certain new and useful Improvements in Spiral Propellers for Ships, of which the following is a specification.

The primary purpose of this invention is 10 the provision of novel propelling means for ships and water craft generally whereby the speed of such carriers is increased and the liability of injury to the propeller reduced by having the same inclosed.

15 In accordance with this invention the propeller is of screw or spiral formation and is inclosed in a suitable casing through which the water is caused to pass, thereby obtaining a two-fold action, the one resulting 20 from drawing the water into the casing and the other from forcing the water from the casing against that in the rear thereof.

With these and other objects in view, which will readily appear as the nature of 25 the invention is better understood, the same consists in the improved construction and novel arrangement and combination of parts which will be hereinafter fully described and particularly claimed.

30 In the accompanying drawings has been illustrated a simple and preferred form of the invention, it being, however, understood that no limitation is necessarily made to the precise structural details therein exhibited, 35 but that changes, alterations and modifications within the scope of the invention as claimed may be resorted to when desired.

Referring to the drawings,—Figure 1 is a view in elevation of a ship provided with 40 propelling means embodying the invention, the casing for the screw propeller being in section; Fig. 2 is a top plan view of a modification; Fig. 3 is a side view of the modification illustrated in Fig. 2; Fig. 4 is a detail 45 view of the propeller on a larger scale; Fig. 5 is a fragmentary view of a further modification; Fig. 6 is a detail view in elevation of the modification shown in Fig. 5.

Corresponding and like parts are referred 50 to in the following description and indicated in all the views of the drawings by the same reference characters.

Referring to Fig. 1, the numeral 1 designates the hull of a ship or sea going vessel. 55 A screw propeller 2 is located in line with the keel of the ship and extends practically

the entire length thereof and is mounted in suitable bearings 3. The screw propeller may be of any construction and comprises a shaft having a flight or wing extending spirally therearound. A casing 4 extending the entire length of the vessel receives the screw propeller 2. The water is drawn into the forward end of the casing by means of the propeller and is forced through the 60 casing and discharged from the rear end thereof by the action of the propeller. The drawing of the water into the casing 4 tends to create a reduced pressure in advance of the vessel which draws the vessel forward 65 while the discharge of the water at the rear of the casing by impact with the water in the rear of the vessel tends to push the latter forward. It will thus be understood that the vessel is actuated by a dual force, the 70 one drawing, the other pushing. By having the propeller incased it is also protected from injury by coming in contact with objects that may be floating in the water. The 75 propeller may be driven in any manner.

In the modification shown in Fig. 2 four propellers 2^a are provided and disposed two upon each side of the vessel, the one at or near the bow and the other at or near the stern. This results in two bow propellers and 80 two stern propellers. The bow propellers are oppositely inclined as are also the stern propellers but the latter incline in an inverse direction to the former. Longitudinal shafts 5 are disposed along the sides of 85 the vessel and are connected at their ends by means of universal joints 6 with the shafts of the respective bow and stern propellers. The several propellers are of like formation, each embodying a shaft 7, a spiral, or 90 screw flight or wing, 8 secured to the shaft 7 and a suitable casing 9, the latter inclosing the propeller proper and being open throughout its length. The shaft 7 may be mounted in anti-friction bearings, as indicated at 10, and such bearings are protected by means of tapering guards 11 which act as deflectors to minimize the resistance of the shaft and bearings to the forward movement 95 of the vessel.

In the modification shown in Figs. 5 and 6 the propeller 12 is similar in formation to the propeller hereinbefore described, the same comprising a shaft and a flight or wing extending spirally therearound. This 100 propeller is preferably disposed in advance of the bow of the vessel and in line with the 105

keel. A casing 13 incloses the propeller 12 and serves to confine the water which is drawn into the casing at its forward end and discharge therefrom at its rear end. 5 Tubular conductors 14 extend along the sides of the bow of the hull 15 and receive the water from the casing 13 with which they connect. The tubular conductors 14 extend for a short distance along the sides 10 of the hull and discharge the water in the rear of the bow. The combined area or capacity of the tubular conductors 14 is about equal to that of the casing 13 so as to carry off the water delivered therein from such 15 casing.

It will be understood that the invention provides a propeller for ships which materially increases the speed thereof without requiring a proportionate increase in the 20 power required for driving the propeller. It is also observed that the propeller being incased is protected from injury from external objects. It is further observed that the action of the propeller is two-fold and 25 serves to propel the boat by creating a reduced pressure in advance thereof and by the impact of the water against that in the rear of the boat so that the vessel is both drawn and pushed forward.

30 Having thus described the invention, what is claimed as new is:—

1. A propeller for boats including a tubular casing, a shaft extending axially of the casing, a spiral propeller blade carried by 35 the shaft, and a substantially conical hood disposed in advance of the casing and free of connection to the shaft, the hood being of less diameter than the casing.

2. In ship propulsion, the combination

with a ship hull, of parallel shafts extending longitudinally of the hull and projecting at their ends through the sides of the hull adjacent the bow and stern, means within the hull for independently rotating the shafts, tubular housings disposed at either side of the bow of the ship and converging forwardly toward each other, helical screw propellers mounted in each of the housings and having universal joint connections with the shafts, tubular housings 40 mounted upon the sides of the hull adjacent the stern and converging rearwardly toward each other, helical screw propellers mounted in the latter housings and having universal joint connections with the shafts, and substantially conical hoods disposed in advance of all the housings. 50

3. In ship propulsion, the combination with a ship hull, of shafts extending longitudinally of the hull and projecting at their ends through the sides of the hull adjacent the bow and stern, means for driving the shafts, tubular housings disposed at either side of the bow of the ship and converging forwardly toward each other, helical screw propellers mounted in each of the housings and having universal joint connections with the shafts, tubular housings mounted upon the sides of the hull adjacent the stern and converging rearwardly toward each other, 60 and helical screw propellers mounted in the latter housings and having universal joint connections with the shafts. 65

In testimony whereof, we affix our signatures.

JOHN J. TOBIN. [L. S.]
FRANK J. GALLAGHER. [L. S.]
